COAT

Isaac Kirschenbaum, Middletown, Pa.

Application March 21, 1934, Serial No. 716,703

2 Claims. (Cl. 2—98)

This invention relates to coats and particularly to an improved coat structure involving a specially formed collar which may be moved into and out of operative position, the object being 5 to provide a construction of collar whereby a coat having a leather or similar outside body portion will have at the same time means which may be moved over the collar part of the body which will present a fabric member.

10 Another object of this invention is to provide a coat having a leather body and collar with a fabric collar formation arranged to be normally folded within the body but capable of being unfolded and positioned to cover the leather collar 15 whether in a turned up or turned down position, whereby the leather collar will not come in contact with the head or neck of the wearer of the garment.

An additional object of the invention is to provide 20 an improved construction of coat and collar which is an improvement over my prior Patent No. 1,804,846, issued May 5, 1931.

In the accompanying drawing—

25 Figure 1 is a perspective view of a coat dis- closing an embodiment of the invention, the coat being shown on a figure as it will appear ordinarily when in use;

Figure 2 is an inside elevation of the upper part 30 of the coat shown in Figure 1, with the leather collar turned up and the fabric collar turned down;

Figure 3 is a sectional view through Figure 2 on the line 3—3;

Figure 4 is a view similar to Figure 2 but showing 35 the fabric collar turned up so as to protect the neck against contact with the leather collar.

Referring to the accompanying drawing by 40 numerals, 1 indicates a coat which is usually made from leather or imitation leather on the outside and then lined with some fabric as, for instance, the fabric 2 as shown in Fig. 2. The lapels 3 and 4 are usually of leather, as is also the collar 5. This gives a complete leather appearance to the garment, while the lining acts to make 45 the garment more comfortable and retain the heat.

The coat 1 and the parts just described are all 50 conventional in style, but if desired the coat could be made in any style of garments of this character. Sometimes coats or garments of this kind are known as lumber jackets, or as outdoor leather coats. While these coats give splendid service, the leather collar is sometimes objectionable 55 because it is cold to the touch and chills the neck and the back of the head when turned up, or even

when turned down and part of the neck contacts therewith. In addition the leather or imitation leather has a tendency to deposit oily substance or objectionable matter on the neck of the wearer, or on the coat or other garment worn underneath the coat 1. The foldover collar 5 is made of material having a cold characteristic, that is, a cold sensation to the touch or when the material touches any part of the body, and may be of genuine leather or imitation leather so that the term "leather" is to be understood as including genuine leather and imitation leather.

To secure the desired appearance and usefulness of a leather coat, and at the same time to secure the comfort of a cloth coat, an auxiliary 5 collar or protecting flap 6 is provided, said collar being of cloth and preferably of the same cloth or fabric as the lining 2, though this is not essential. The collar 6 is stitched in place by lines of stitching which also hold the leather collar in place. The auxiliary collar 6 is preferably made of a width to reach almost to the outer edge of the collar 5 when both the collar 5 and the auxiliary collar 6 are turned up, as shown in Fig. 4. By reason of the stitching 7 the auxiliary collar 6 swings back and forth on the stitching 7 which is an arc-shaped line to conform to the shape of the coat.

The ends of the auxiliary collar 6 extend over 30 part of the lapels 3 and 4 so that they will be substantially opposite the ends 9 and 10 of collar 5. Preferably the auxiliary collar 6 is wider at the center than at the ends so that when it is turned from the position shown in Figs. 2 and 3 to an upper position as shown in Fig. 4, the upper edge 11 will be substantially parallel with the upper edge 12 of the collar 5. In this manner the desired usefulness of the collar 5 will be secured and also the desired appearance, while the auxiliary collar 6 protects the neck and head against contact with collar 5, thereby making the garment more comfortable.

It will be understood that the garment can be worn at any time with the auxiliary collar 6 turned down as shown in Fig. 2, and the collar 5 turned down as shown in Fig. 1. However, it is preferable when the coat is buttoned up and the collar 5 turned down as shown in Fig. 1, or turned up as shown in Fig. 5, that the auxiliary collar 6 is also in use as illustrated in Fig. 1.

In my prior patent above mentioned the parts are made separable and secured together by snap fasteners or similar means, the body of the coat being open to receive the parts of the collar, whereas in the present invention the auxiliary 55

collar 6 is to be permanently fastened in position interiorly of the coat with the line of stitching which secures the permanent collar 5 to the body of the garment. This arrangement permits 5 the auxiliary collar to be left in its downward position and the coat used in the usual manner, or permits the auxiliary collar to be turned up and acting as a lining for the collar 5.

I claim:

10 1. A coat comprising a body, a foldover collar having a leather outer surface, a seam along one edge of the collar securing the collar to the body, and a fabric protecting flap secured along one of its edges to said body at said seam, said flap being

swingable about its secured edge to overlap said leather surface when in one position, and to lie within said body when in a second position.

2. A coat comprising a body, a foldover collar formed with an outer surface of a material having a cold characteristic, a seam along one edge of the collar securing the collar to the body, and a fabric protecting flap secured along one of its edges to said body at said seam, said flap being 5 swingable about its secured edge to overlap said outer surface when in one position, and to lie within said body when in the second position.

ISAAC KIRSCHENBAUM.
